CLAIM

The ornamental designs for a front grille for a vehicle, as shown and described.

DESCRIPTION

FIG. 1 is a front left elevated perspective view of a front grille for a vehicle, showing my new design;

FIG. 2 is a front left perspective view thereof;

FIG. 3 is a rear right elevated perspective view thereof;

FIG. 4 is a rear right perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is another front view of the front grille for a vehicle shown mounted on a vehicle;

FIG. 12 is a front left elevated perspective view of another embodiment of a front grille for a vehicle;

FIG. 13 is a front left perspective view thereof;

FIG. 14 is a rear right elevated perspective view thereof;

FIG. 15 is a rear right perspective view thereof;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof; and,

FIG. 22 is another front view of the front grille for a vehicle shown mounted on a vehicle.

The broken line showing is for the purpose of illustrating environmental structure and forms no part of the claimed designs.
